United States Patent Office

Des. 192,756
Patented May 8, 1962

192,756

BOTTLE CARRIER

Clare E. Hodgman, Mamaroneck, N.Y., assignor to The Coca-Cola Company, Atlanta, Ga., a corporation of Delaware

Filed Sept. 20, 1960, Ser. No. 62,204

Term of patent 14 years

(Cl. D58—26)

FIG. 2.

FIG. 4.

The opposite side and end of the carrier are identical to the side and end shown.

I claim:

The ornamental design for a bottle carrier, as shown and described.
